UNITED STATES PATENT OFFICE.

LOUIS T. FENNING, OF JACKSON, OHIO.

TIME-CONTROLLED ELECTRIC-SWITCH MECHANISM.

Application filed July 18, 1923. Serial No. 652,348.

This invention relates to improvements in electric switches and particularly to electric switches that are time-controlled, that is to say, clock-operated. An object of this invention is to provide a clock-operated electric-switch which will be simple in construction and comparatively cheap in manufacture and therefore susceptible of being sold at a relatively low price, and which will 5 prove reliable, efficient and durable in operation and use, and the cost of upkeep of which will be trifling. Another object of this invention lies in the provision of an inexpensive time-switch controlled by clockwork 10 that differs in the main not greatly from the clockwork employed to operate the alarm mechanism of the ordinary so-called nickel alarm-clocks heretofore and now on the market in this country; in other words, 15 the clockwork that regulates the movement of the switch-elements by which the electric circuit is closed and interrupted alternately and at predetermined hours is one that results from embodying a few slight alterations 20 in and making a small number of simple additions to the clockwork used in present-day alarm-clocks for timing the ringing of the alarm-bell at the hour desired by the user.

30 In the drawings illustrating the principle of this invention and the best mode now known to me of applying that principle,

Fig. 1 is a general view in elevation of the switch mechanism suitably mounted;

35 Fig. 2 is a rear elevation of the clock;

Fig. 3 is a vertical section approximately on the line 3—3, of Fig. 2;

40 Fig. 4 is a front elevation of the clock-work gear-trains, the clock-casing being omitted or removed;

Fig. 5 is a vertical section on the line 5—5, of Fig. 3;

45 Fig. 6 is a detail of mechanism involved in the interruption of the electric circuit;

Fig. 7 is a detail of parts of the same mechanism in another position;

50 Fig. 8 is a fragmentary detail of the clock-face and shows the dials by which the apparatus is set to close and open the electric circuit, at certain predetermined times;

Fig. 9 is a detail of the switch-indicator in elevation;

Fig. 10 is a detail of the switch-spindle drive;

55 Fig. 11 and Fig. 12 are detail views that

illustrate, in different positions, mechanism involved in the closing of the circuit; and

Fig. 13 is a diagrammatic view of the electric circuit.

The framework by which the clockwork mechanism is supported includes (Figs. 3, 4 and 5) two rectangular-shaped frame-plates, namely, a front frame-plate *a* and a back frame-plate *b*; these frame-plates *a*, *b*, are held in spaced relation to each other by 60 spacing cross-rods (sometimes called pillars) *c* that are positioned near the corners of the frame-plates *a*, *b*. In the latter, there is mounted rotatably a drive-shaft *d* around which there is coiled a helical motor-spring *e* one end of which is fastened to the shaft *d* and the other end of which is secured to one of the lower plate-holding spacing-rods or pillars *c*. Mounted fast upon the shaft *d* there is a ratchet-toothed wheel *f*, with the ratchet-teeth *f'* of which engages the free nose-end of a spring-pressed click or pawl *g*. The other end of this pawl *g* is pivotally fastened to one of the radial arms *h* of a toothed wheel *h* that is mounted on the shaft *d* idly (or free to turn thereon). Hence, when this shaft *d* is turned by the expansion of the motor-spring *e*, the ratchet-wheel *f* turns with it; and the direction of rotation is 65 such that the pawl *g* is engaged by ratchet-teeth *f'* and thus serves to drive the spur-wheel *h* that is mounted idly on the shaft *d*. The latter shaft extends rearwardly through the back frame-plate *b* and its end *d'* that projects therethrough is fitted with a winding-key *i* which is provided with a milled thumb-and-finger hold or head *i'* (Fig. 3). By turning the winding-key *i*, the shaft *d* may be turned to wind up the helical motor-spring *e*. While the spring *e* is being thus 70 wound, the free nose-end of the pawl *g* rides idly over the ratchet-teeth *f'*, as the ratchet-wheel turns with the motor-spring shaft *d*. The nose-end of the pawl *g* is held pressed against the ratchet-teeth *f'* by a spring *j*, which is carried by the spur-wheel *h*, as is 75 also the pawl *g*. Extending parallel with the motor-spring shaft *d*, there is a fixed or stationary shaft *k* the extremities of which are mounted in the frame-plates *a*, *b*, and upon which there are mounted, free to rotate, a spur-gear *m* and a pinion *n* that is of the type of wheel known as a lantern-wheel (Fig. 3) and that is in mesh with the spur-wheel *h*, by which it is driven. The two 80

toothed wheels m , n , are so joined together as to be for all practical purposes integral with each other; therefore, they rotate together or in unison upon the fixed shaft k .

5 Parallel with the two shafts d , k , there extends a shaft o which lies above the shafts d , k , and the extremities of which are rotatably mounted in the frame-plates a , b ; both of the frame-plates a , b , being formed with 10 downwardly-projecting ears a' , b' , in which the two ends of the shaft o are received. (See Fig. 5). Mounted fast upon this rotary shaft o , there is a pinion p , which is of the lantern-wheel type and which is in mesh 15 with the spur-wheel m and is driven by the same. On this rotary shaft o there is further fixed a toothed wheel q that is sometimes called a verge-wheel and with which coact, in a well-known manner, the free ends 20 r' , r'' , of a double nosed pawl or dog r that is known as a verge. The verge r is carried by a rock-shaft s that is known as a verge-shaft. The ends s' of this shaft s are reduced, so that the shaft is formed with shoulders s'' (Figs. 6 and 7), and are mounted 25 in the frame-plates a , b , so that the shaft s may rock and may also be shifted or displaced lengthwise, the shoulders s'' , by their abutting against the frame-plates a , b , serving 30 to limit this lengthwise displacement. In well-known types of alarm-clocks, the striker or hammer is carried by the verge-shaft.

Centrally disposed with respect to the 35 frame-plates a , b , and mounted therein free to turn, there is a shaft t , which, from the nature of its function, may be called the clockhands-positioning shaft. Inasmuch as the time-train motor-spring and the parts of 40 the time-train that are involved in the drive of the shaft t and are themselves actuated by the expansion of the time-train motor-spring, are so well-known to all persons skilled in this art, such motor-spring and time-train 45 parts have been neither illustrated nor described herein; and it will be understood that any one of the many forms of gearing-trains used commonly in this art for causing the clockhands to sweep over the clockface, may 50 be employed for the same purpose in the clockwork of the particular embodiment of this invention that is herein shown. This shaft t may, therefore, be regarded as a conventional representation of time-train mechanism that has for its office to cause the 55 clockhands to travel over the dial-plate. As is usual in the construction of clocks of the alarm-clock type, the shaft t is arranged so that it may be employed for the manual setting 60 of the clockhands by the user of the clock; and, to enable the user to turn the shaft t , it is made of such length that it projects rearwardly beyond the back frame-plate b (Fig. 3), where its projecting rear- 65 end is fitted with a setting-key v the thumb-

and-finger hold v' of which is milled. Mounted fast on the shaft t and positioned just in front of the front frame-plate a , there is a small toothed wheel or pinion u the teeth of which mesh with the teeth of a spur-wheel w that is mounted loose on a stud or stub-shaft w' which extends forwardly from the front frame-plate a . Substantially integral with the spur-gear w is a pinion x that lies in front thereof and is mounted idly on the arbor w' and the teeth of which are in mesh with the teeth of a spur-gear y that is mounted idly or loose on the clockhands-setting shaft t and with which is substantially integral a somewhat smaller spur-gear z (Fig. 4) that is arranged in front of the gear y and is likewise free to rotate upon the clockhands-driving shaft t . This spur-wheel z lies just in rear of the clockface 2 and is formed with an elongated, forwardly-extending hub z' that projects therethrough (Fig. 3) and upon which is mounted the hour-hand 3. The front end of the clockhands-positioning shaft t projects through the clockface 2 and, upon the front extremity of this shaft t , there is mounted the minute-hand 4. As the shaft t is caused to rotate in the frame-plates a , b , by the main spring of the clock acting through the time-train of gearing (hereinbefore mentioned but not illustrated herein because of its being thoroughly familiar to all persons skilled in this art), the minute-hand 4 moves over the clock-dial 5 formed on the clockface 2 and the pinion u turns with the shaft t and causes to turn the spur-wheel w and the pinion x mounted loose on the arbor w' . Rotation of the pinion x produces rotary motion of spur-wheel v in mesh with it and also of the spur-gear z that is substantially integral with the gear y and on the elongated hub z' of which is mounted the hour-hand 3. Projecting forwardly from the front frame-plate a , there is a stud or arbor 6 upon which there is mounted free to rotate a toothed wheel 7 (Figs. 3 and 4) the front face of which carries an indicator-card 8, one half of which is shaded black and the remaining half is left white. Along the diameter that divides the dark half from the light half of the circular card 8, there are marked the abbreviations, AM, and PM, while along the diameter that runs at right angles to the diameter just mentioned, the word, Noon, appears on the card 8, in the light semicircle (Fig. 4). In the clockface-plate 2, there is formed a small aperture 8' through which may be observed the indicator-card 8 and at which appear, at regular intervals, the abbreviations and the word just mentioned, as the card 8 turns during the rotation of the toothed wheel 7; that is, the abbreviation, AM, shows squarely at opening 8' at six o'clock in the forenoon, the word, Noon, comes fully into view six hours later, and

abbreviation, PM, may be clearly seen at six o'clock in the evening. When only the white half of the card 8 is visible through the aperture 8', one may be sure that the hour indicated by the clock is between six o'clock in the morning and the same hour in the afternoon; while, when only the dark half of the card 8 shows at the opening 8', the hour indicated is later than six o'clock in the evening; that is, speaking broadly, day-time hours are indicated by white being seen through the opening 8', while night-time hours are signified when black is visible therethrough. The toothed wheel 7 is in mesh with the smaller toothed wheel 2, the elongated hub 2' of which carries the hour-hand 3 and which drives the wheel 7.

Projecting from the front frame-plate *a*, there is a pair of studs or arbors 9, 10, upon which turn a pair of intermeshing transmission-pinions (or carrier-pinions) 11, 12, respectively. The pinion 11 of this pair is in mesh with and driven by the spur-gear *y* that is mounted idly on the centrally-disposed, clockhands-driving shaft *t*, while the other carrier-pinion of this pair 11, 12, meshes with a spur-gear 13 that rotates freely upon the stub-shaft 14 projecting from the front frame-plate *a* (Figs. 3 and 4). Idly mounted upon this stub-shaft 14 and substantially integral with the spur-gear 13 so as to turn therewith on the shaft 14, there is a smaller toothed wheel or pinion 15, the teeth of which are in engagement with the teeth of a spur-wheel 16 mounted free to turn on the front end of a setting-shaft 17 the rear end of which projects beyond the rear frame-plate *b* and is provided with a milled thumb-and-finger head 18, by grasping and turning which the shaft 17 may be turned. The toothed wheel 16 mounted idly thereon is provided with a ringlike, forwardly-projecting hub 16' which is formed with a recess and the front end or face of which is formed with a cam 16'', so that the recessed hub 16' is, for all practical purposes, a ring-cam. In the cam-edge 16'' there is formed a notch or depression 19 that is shaped to receive a cam-lug 20 that projects laterally from a collar 20' fixed upon the front end of the setting-shaft 17. Extending upwardly and obliquely to the left, as viewed in Fig. 4, there is a flat or leaf spring 21, the lower end of which is fixed to the front frame-plate *a* at a point to the right of the center thereof (as viewed in the same figure) and the upper end 21' of which is formed with a hole through which passes the setting-shaft 17. This leaf-spring 21 tends to press the toothed wheel 16 to the front along the setting-shaft 17 and thereby to maintain the cam-edge 16'' in rubbing contact with the cam-lug 20, and, for the performance of this function, the upper end 21' of the spring 21 lies in front of the frame-plate *a* and directly in

rear of the spur-wheel 16. As the time-train drives the clockhands-controlling shaft *t* and as, by the gear-train propelled by the pinion *u* and including the transmission-pinions 11, 12, the spur-gear 16 is rotated on the setting-shaft 17, the gear 16 is forced forwardly along the latter shaft by the spring 21 when the cam-notch 19 arrives opposite to or in register with the cam-lug 20, whereupon, as will hereinafter be described, the electric circuit is closed, and, for this reason, the toothed wheel 16 may be correctly designated the On-control wheel or gear. Lying parallel to the On-setting shaft 17 and above and to the left of the same, (as viewed in Figs. 3 and 4) and mounted in the frame-plates *a*, *b*, free to rotate, is a second setting-shaft 22 the rear end of which extends rearwardly and is provided with a thumb-and-finger head or hold 22' that is milled and that may be grasped and turned. The other or front end of this setting-shaft 22 projects forwardly beyond the front frame-plate *a* and carries a fixed collar 23' from which projects laterally a cam-lug 23. The similarity in construction between the two setting-shafts 17, 22, will be obvious from an inspection of Fig. 3, in connection with the foregoing description of these shafts. Upon the front end (Figs. 3 and 4) of the setting-shaft 22, there is mounted, free to rotate thereon, a toothed wheel 24 that is formed with a forwardly-projecting hub 25, which is provided in its front end, with a recess within which may be received the collar 23' that is fixed on the front end 100 of the setting-shaft 22. The front end or face 25' of the recessed hub 25 is cam-shaped, so that the hub 25 serves as a ring-cam, and, in this cam-edge 25', there is formed a depression or notch 26, which is, by the rotation of the spur-wheel 24, brought opposite to or in register with the cam-lug 23. The similarity in construction that exists between the toothed wheels 16, 24, becomes plain from an inspection of Fig. 4, when made in connection with the foregoing description of these wheels. As is best shown in Fig. 4, the spur-wheel 24 is driven by the spur-wheel 16, through the intermediary of a wide-faced pinion 27 that is mounted, free 110 to turn, on an arbor or stud 27' projecting forwardly from the front frame-plate *a*. Secured at its lower end to the latter, near the left-hand edge thereof (as viewed in Fig. 4), there is a flat or leaf spring 28 which is 120 practically vertically-disposed and the upper end of which bears upon the front end of the lengthwise-slidable, verge-carrying rock-shaft *s* hereinbefore mentioned. This rock-shaft *s* corresponds in some essential respects 125 to the verge-shaft of the common so-called "nickel" alarm-clocks of the present time. In the front end of this rock-shaft *s*, there is formed a ringlike or circumferential groove 29 (see Figs. 6 and 7) with the walls 130

of which engages the lower bifurcated end 30' of a flat-metal bent lever 30 which, as viewed in Fig. 4, extends obliquely upwards and to the right and lies in front of the 5 front frame-plate *a*. The upper end of this bent lever 30 is formed with a hole through which passes the setting-shaft 22 (Figs. 4, 6 and 7), so that this upper end is interposed between the frame-plate *a* and the toothed 10 wheel 24. The mid-portion 30'' of the bent lever 30 rests or bears against the frame-plate *a* and serves as a fulcrum-point about which the lever 30 rocks or tilts in the operation of the circuit-interrupting mechanism. 15 As the toothed wheel 24 turns, the notch 26 cut in the cam-edge 25' is brought closer and closer into register with the cam-lug 23 formed on the fixed collar 23' (Fig. 7 shows the notch and cam-lug about to come into 20 register with each other); and, finally, when the cam-lug 23 and the cam-notch 26 come exactly opposite each other, the tension of the almost upright leaf-spring 28 becomes free to act and forces the lengthwise-slid- 25 able rock-shaft *s* to the rear (that is, from its position shown in Fig. 7 to its position illustrated in Fig. 6), the bent lever 30 is tilted on its mid-part 30'' and the spur-wheel 24 is pushed along the setting-shaft 22 to 30 the front, whereupon the fixed collar 23' is received within the recessed hub 25 and the cam-lug 23 enters the indentation or depression 26 in the cam-edge 25' (Fig. 6). As will 35 hereinafter be more particularly explained, the shifting of the rock-shaft *s* longitudinally to the rear results in the interruption of the electric circuit; and the toothed wheel 24 may properly be termed the Off-control 40 wheel or gear and the setting-shaft 22 may be called properly the Off-setting shaft.

In addition to the clock-dial 5, the clock-face-plate 2 bears two other dials 31, 32, which may be designated setting dials, the dial 31 being called the On-setting dial, and the dial 32 being named the Off-setting dial, 45 because of the functions performed respectively by these dials 31, 32. At the center of the On-setting dial 31, the clockface-plate 2 is formed with a hole (Figs. 3 and 8) 50 through which projects the front extremity of the On-setting shaft 17 that carries a setting-hand or pointer 31' which, as the shaft 17 is turned, sweeps over the dial 31 (Figs. 1 and 8). This dial includes a graduated 55 circle 31'' having twenty-four main (or hour) divisions, each of which is bisected and which are numbered consecutively from 1 to 12 and again from 1 to 12, or in two 60 equal twelve-number series that follow each other, in going around the circle. That part of the dial 31 that lies below the diameter joining the diametrically-opposite numerals 6, 6, thereon, is blackened and bears in white letters the word, Night, while the 65 part of the dial 31 lying above this diameter

is left white and bears the words, Noon, Day and On, which appear one below the other in the order given and all under the upper numeral 12. Further, just above this diameter, there are shown the two abbreviations, AM and PM, the abbreviation AM appearing adjacent to the numeral 6 that is at the left (as viewed in Fig. 8) of the center of the circle, while the abbreviation PM is shown near the other numeral 6 at the 70 right of that center. The On-pointer 31' extends in the same direction as does the cam-lug 20, which projects from the collar 20' fixed on the front end of the On-setting shaft 17; that is, the hand 31' is so positioned, 75 when it is fastened on the extremity of the latter shaft, that it ever points in the same direction as the cam-lug 20. In shading the lower part of the dial 31, the somewhat arbitrary assumption is made that the hours 80 from six o'clock in the evening until six o'clock in the morning are night-time hours, while the remaining twelve hours of the day are day-time (or daylight) hours. By seizing the milled button 18 that is on the end 85 of the On-setting shaft 17 and turning the same in the direction indicated by the arrow shown on the dial 31 in Fig. 8, the pointer 31' may be set to indicate the hour at which the circuit is to be closed (that is, for example, the time at which it is desired to turn on the electric lights in a store show-window). The other dial 32 is substantially identical with the On-dial 31, except that where the word On shows on the latter dial, 90 the word Off appears on the dial 32, which may be designated as the Off-dial. The front end of the Off-setting shaft 22 projects through a hole 22' (Fig. 3) in the clockface-plate 2 and, upon this end, there is fastened 95 a pointer 32' which extends parallel to the cam-lug 23 and which serves to indicate the hour at which it is intended to interrupt or break the electric circuit (that is, for example, the time at which the electric lamps 100 in a show-window are to be turned off or darkened). The Off-indicator 32' is turned to the desired hour shown on the Off-dial by grasping the milled head 22' on the rear end of the Off-setting shaft 22 and rotating 105 the same in the direction of the arrow shown on the Off-dial in Fig. 8, until the Off-hand 32' points to that hour.

To the rear frame-plate *b*, there is fastened a switch-supporting block 33 that is 110 made of suitable electric-insulation material and formed with a recess 34 within which there is fitted securely an electric switch 35 which, in the embodiment of this invention herein shown and described, is of 115 the well-known type commonly known as a snap switch. The shaft or spindle 36 of the electric snap-switch 35 is rotatable and carries an elongated metal contact-plate (or switch-blade plate) 37 that extends at 120

right angles to the switch-spindle 36 and is formed, at each of its two ends, with a contact-tongue or finger 38. When the electric circuit is closed through the snap-switch 35, the contact-plate 37 bridges the gap between the terminal contact-members 39 of the switch, which are mounted on the switch-block 33, the contact-fingers 38 then engaging the terminal-contacts 39; but, when the electric circuit is interrupted, the switch-blade plate 37 is thrown around ninety degrees from its closed-circuit position and there is a gap between the terminal-contacts 39 (see Fig. 5), in which position of the switch-blade plate 37 its longitudinal axis lies at right angles to a line joining the terminal contact-members 39. This displacement of the switch-blade plate 37 is effected by turning the switch-shaft 36, which, in an ordinary manually-operated snap-switch, is accomplished by seizing and turning a turn-button mounted on one end of the shaft. In the electric snap-switch 35, the spindle 36 is rotated from the drive-shaft *d* (Fig. 3) that is actuated or propelled by the expansion of the motor-spring *e*, the rotary movement of the drive-shaft *d* being transmitted to the switch-operating shaft 36 through the following-described gear-train, to-wit: The front end of the switch-actuating spindle 36 extends forwardly just beyond the rear frame-plate *b* and carries a fixed spur-gear 40 that is in mesh and driven by a smaller spur-gear 41 which is mounted, free to turn, on the drive-shaft *d* and upon the front face of which there is secured a spring click or pawl 42 the nose-end of which is pressed, by the inherent resiliency of the click itself, firmly against the teeth of a pinion 43 which is mounted fast upon the drive-shaft *d* and therefore rotates therewith. When the drive-shaft *d* is turned, by seizing and turning the milled button *i*, in such a direction as to wind up the motor-spring *e*, the teeth of the pinion 43 slip under the nose of the spring pawl 42 without there resulting any engagement of such teeth with the latter, so that the toothed wheel 41 remains motionless while the motor spring *e* is being wound up; but, when due to the expansion of the motor spring *e*, the drive-shaft *d* is caused to rotate in the opposite direction, the teeth of the pinion 43 do engage the nose-end of the spring-pawl 42, so that, as the pinion 43 turns with the drive-shaft *d* under the influence of the tension of the expanding motor-spring *e*, the spur-gear 41 turns with the drive-shaft *d* upon which it is idly mounted and causes the spur-gear 40 and the switch-actuating shaft 36 to rotate. Carried by the switch-blade plate 37 but electrically-insulated therefrom, there is provided an elongated switch-shaft arrester-plate 44 the ends 44' of which are tongue-like, that is, thin and flat. It may be here said that, as will be hereinafter more fully explained, the switch-blade plate 37 also serves to arrest the rotation of the switch-actuating shaft 36, when its contact-tongues 38 are disengaged from the terminal contact-plates 39, that is, when the electric circuit is opened at the switch (Fig. 5). The arrester-plate 44 is located in front of the contact-plate 37 that carries it, that is, it lies nearer the bottom of the switch-receiving recess 34 formed in the switch-supporting block 33; hence, when the plate 44 is thrown into the position illustrated in Fig. 5, it does not make electrical contact with the terminal-plates 39 and remains at all times out of the plane of the latter. As shown in Fig. 5, the longitudinal axes of the plates 37, 44, are at right angles to each other. On the outer end of the switch-actuating shaft 36, there is mounted a circular indicator-plate 45, the outer (or rear) face of which is divided into four parts (Figs. 2 and 9), or sectors, two of which are shaded black and lie on opposite sides of the center of the plate 45, while the other two sectors are left white. The blackened sectors bear the word Off, while the white sectors are marked with the word On. In the back-plate 46 of the clock-casing 47, there is formed an opening 46' through which the indicator plate 45 is in part visible and before which appears one of these words, Off, On. When the electric circuit is closed through the switch, the word On shows at the opening 46', while when the electric circuit is open, the word Off therethrough is seen (Fig. 2), so that the condition of the circuit at the switch may be at all times determined by a glance at the opening 46'. Parts of the switch mechanism that, in addition to the switch elements already described, play a part in the production of the so-called snap-action of the switch are illustrated only schematically in the drawings and are marked S therein, and their construction and mode of operation are so well known and understood by all persons skilled in this art as to require no further detailed description or illustration herein, except to say that there is wound around the switch-actuating spindle 36 a helical spring 47' the outer end of which is fastened thereto, while its other or inner end is secured to the herein conventionally illustrated mechanism S.

Carried by the front end of the lengthwise-slidable rock (or verge) shaft *s* there is a rocker-arm 48 the body-part of which extends in a substantially horizontal direction towards the vertical mid-plane of the clock (see the dotted-line position shown in Fig. 5) and the inner free end of which is arranged to rest upon the upper extremity 21' 130

of the leaf-spring 21, which, for this purpose, is bent inwardly (or rearwardly) and forms a lug 21'' from which projects rearwardly a finger 21* (see Figs. 6, 11 and 12), 5 upon which finger the end of the rock-shaft 48 is supported, when the cam-lug 20 is rubbing against the raised part of the ring-cam 20'. As has hereinbefore been explained, the spring 21 is maintained 10 compressed, until the cam-lug 20 and the cam-notch 19 are brought into register with each other (Fig. 11). When the cam-lug 20 arrives opposite the cam-notch 19, the tension of the spring 21 is free to act and forces 15 the On-control gear 16 to the front (Fig. 12). The upper free end of the spring 21 jumps away from the front frame-plate *a* and the support afforded the free end of the rocker-arm 48 by the finger 21* is withdrawn. 20 To the other or rear end of the same rock-shaft *s*, there is fastened the upper end of a bent rocker-arm 49 the body part of which is substantially vertically-disposed (Figs. 5 and 6) and the lower end 50 of which is 25 bent at right angles to the body-part or leg and is made comparatively flat and wide, somewhat after the shape of the end of a spatula (Figs. 5 and 6). When both the On-setting shaft 17 and the Off-setting shaft 30 22 have been turned to set their respective pointers 31', 32', at the hours (shown on the dials 31, 32) at which the electric circuit is to be first closed and afterwards interrupted, respectively, and the electric circuit is open 35 at the switch 35 (Figs. 2, 3 and 5), the rocker-arm toe 50 lies in the plane of rotation of the switch-shaft arrester-plate 44, which position is that indicated by the dotted lines in Fig. 6, and in Fig. 3. In this position of 40 the rocker-arm toe 50 relative to the thin tongue-like ends 44' of the arrester-plate 44, the rocker-arm 49 may be made to oscillate or vibrate. When, under these conditions, the finger 21* is disengaged from the 45 free end of the rocker-arm 48, which is thereby left free to oscillate also, the release of the verge *r* is complete and the verge-wheel *q* is free to rotate and is driven, by the expansion of the motor-spring *e*, from 50 the main drive-shaft *d* through the gear-train that includes the toothed wheels *f*, *h*, *n*, *m*, *p* (Fig. 3). The rotary movement of the drive-shaft *d* is communicated to the switch-actuating spindle or shaft 36 by the pinion 55 43, which is pawl-coupled to the spur-wheel 41 that is in mesh with the gear 40 fast on the front end of the switch-shaft 36. The rotation of the latter effects the same result, so far as the electric circuit is concerned, as is produced by turning the button of an ordinary snap-switch; that is, in the case assumed, the switch-blade plate 37 is thrown around through ninety degrees, whereby its contact-tongues 38 are brought 60 into engagement with the terminal-contacts 39, and the electric circuit is closed. Another result following the rotation of the switch-turning shaft 36 is the automatic arresting of the same, which is brought about by the operation of the following parts, to-wit: 70 We have seen that, during the rotation of the switch-driving spindle 36, the crown-wheel (or verge-wheel) *q*, by the alternate engagement and disengagement of its teeth with the nose-ends *r'*, *r''* of the double-nosed 75 pawl or verge *r*, swings the rock-shaft *s* back-and-forth and maintains the rocker-arms 48, 49, in a state of rapid vibration or oscillation, the paths of these rocker-arms being unobstructed. The back-and- 80 forth path of travel of the rocker-arm toe 50 is in the plane of the switch-shaft arrester-plate 44, at the time assumed, that is, the period during which the switch-throwing shaft 36 is being turned just prior to the 85 closing of the electric circuit, as described in the foregoing. When the snap action of the switch takes place and the circuit-closing plate 37 is displaced ninety degrees from its position illustrated in Fig. 3, the arrester- 90 plate 44 carried thereby is likewise displaced through the same arc, whereby one of its tongue-like ends 44' is interposed in the path of vibration of the rocker-arm toe 50 and prevents further oscillation of the rock-shaft *s*. The verge *r* mounted fast on the latter shaft locks the verge-wheel *q* against further rotation and the drive-shaft *d* and switch-actuating shaft 36 come to rest. The 95 switch-shaft stop-arm 49 remains in this position (i. e., with its toe 50 abutting against an end 44' of the arrester-plate 44), until the cam-lug 23 is brought into register with the indentation 26 in the cam-edge 25' by the 100 rotation of the hub 25 of the Off-control wheel or gear 24 (Fig. 6), at which time the latter is pressed forwardly along the shaft 22 by the tension of the leaf-spring 28 acting upon the rock-shaft *s* and the bent lever 105 30 that is interlocked therewith, as hereinbefore described. The rock-shaft (or verge-shaft) *s*, in this movement, is shifted lengthwise to the rear; and it carries the switch-shaft stop-arm 49, which is fast upon it, in the same direction and the toe 50 thereof out 110 of abutting engagement with the obstructing end 44' of the arrester-plate 44 and into the plane of rotation of the circuit-making plate 37. While the Off-control spur-wheel 115 24 has been turning to bring the cam-notch 26 opposite the cam-lug 23, as just mentioned, the On-control wheel 16 has also been rotating (in fact, the spur-wheel 16 drives the spur-wheel 24 through the transmission-pinion 27), and, during such rotation, the 120 cam-lug 20 has moved (relatively) and no longer lies in the cam-notch 19 but rides now out thereof on the cam-edge 16'' (compare Figs. 11 and 12), with the result that the 125 spur-wheel 16 has been forced towards the 130

front frame-plate a and the upper end 21' of the leaf-spring 21 has been pressed inwardly and carried with it the catch-finger 21*. Despite this change in the position of 5 the latter member, amounting in a broad sense to its restoration to the position it had before it was withdrawn or tripped to permit the On-release arm 48 to swing freely, the arm 48 is now again free to swing freely; 10 for, the rearward shifting of the rock-shaft s just described has caused the arm 48 thereon to be displaced and carried to the rear and away from the catch-finger 21*. Hence, it will be seen that both rocker-arms 15 48, 49, are again free to vibrate, their paths of oscillation being once again unobstructed and the verge-wheel or crown-wheel q is made free to turn and does turn, being driven again by the drive-shaft d , which produces rotation of the switch-throwing shaft 36 also, through gear-trains already named in connection with the description of the turning of the latter shaft in the closing 20 of the electric circuit. When the spindle 36 has been turned until the snap-action of the switch 35 occurs, there is produced another displacement of the circuit-closing plate 37 through a quarter-turn and the circuit is interrupted, the plate assuming its position in 25 Fig. 5. The switch-shaft stop-arm 49 has been vibrating in the plane of rotation of the circuit-closing plate 37 and, by the throwing of this plate out of electrical contact with the switch-terminals 39, one of its 30 ends 38 is projected into the path of movement of the toe 50, blocking that path and bringing the stop-arm 49 to rest. One of the ends r', r'' , of the verge r remains in engagement with the verge-wheel or crown-wheel q 35 and locks the same against further rotation. This locking of the crown-wheel q and its shaft o prevents further rotation of the drive-shaft d and so of the switch-throwing 40 spindle 36 propelled by it. The time-train conventionally represented by the clock-hands-positioning shaft t continues to drive the switch-control (or On-control and Off-control) gears 16, 24; and the cam-lug 23 rides (relatively speaking) out of the cam-notch 26 up onto the cam-edge 25' of the ring-cam or hub 25. The actual result of the 45 continued rotation of the spur-gear 24 is to force the same rearwardly and axially along its shaft (the Off-setting shaft 22), whereby the bent lever 30 is tilted on its mid-part 30'' and the grooved end of the rock-shaft s is carried to the front by the forked end 30' of the lever 30 against the tension of the upright leaf-spring 28 (compare Figs. 5 and 7). The forward lengthwise movement of the rock-shaft s carries the rocker-arms 48, 49, to the front, also; but, owing to the broadened extremity of the flat toe 50 of the stop-arm 49, the toe 50 is not released 60 from its abutting engagement with the tongue-like contact-end 38 of the circuit-closing (or switch-blade) plate 37 immediately. When the toe 50 does finally clear the end 38 with which it has been in abutting engagement, the inner or free end of 70 the On-release arm 48 has been moved forwardly a sufficient distance to bring it over the catch-finger 21*, which then supports it and prevents its vibration and so locks the rock-shaft s , until the catch-finger 21* 75 is withdrawn from its supporting position by the forward springing of the leaf-spring 21, when the cam-lug 20 and the cam-notch 19 are again brought into register with each other by the rotation of the On-control spur-gear 16 and its hub, the ring-cam 16', as hereinbefore set forth. 80

In Fig. 13, there is shown a diagram of the electric circuit 55 that is controlled by the clock-operated time-switch C herein described and shown. One of the line conductors 55' leads from any suitable source of electric energy (e. g., the battery P) to a bank or group of electric lamps schematically depicted at L, Fig. 13, and thence to a terminal post 56 (see also Fig. 5) of the electric block or plug 54. One of the switch-terminal-plates 39 is electrically united to the electric-block terminal-post 56 through a binding-wire 57, while the other terminal-plate 39 is electrically joined, by a second binding-wire 57', with the other terminal-post 56' of the electric-plug 54. These wires 57, 57', are within the metal cylindrical sidewall 46'' of the clock-casing 47, between 90 which and the electric-block 54 there is interposed a block 58 (Fig. 5) of electric insulation. But any suitable means of connecting the time-switch C with the line-wires 55', 55'', may be used, without departing 100 from this invention, instead of the particular electric-block 54 shown in Fig. 5. From the terminal-post 56' of the latter, the line-wire 55'' runs back to the source P of electric power. 105

In the following brief description of the operation of the time-switch C, it is assumed that, as is indicated by the position of the clockhands 3, 4, (Fig. 1), the hour is between twenty and twenty-five minutes after five o'clock, and that, furthermore, as is shown by the symbol PM now almost completely visible at the clockface-opening 8', the time of day is afternoon. As is indicated in Fig. 8, by the position of the On-pointer 31' relatively to the On-dial 31, the On-setting shaft 17 has been adjusted so as to bring about the closing of the electric circuit 55 at the switch 35 at the hour of eight o'clock in the evening. Similarly, the Off. 115 indicator 32' is pointing to the hour of six o'clock the following morning, it having been set by its shaft 17 so that the electric circuit will be interrupted at that hour and the lamps L will be darkened. When the hour 120

65 70 75 80 85 90 95 100 105 110 115 120 125 130

of eight o'clock in the evening arrives, the cam-notch 19 formed in the cam-edge 16' of the ring-cam or hub 16' of the On-control spur-wheel 16 comes exactly into register 5 with the cam-lug 20 projecting from the collar 20' fixed on the shaft 17, and, as a result, the tension of the flat spring 21 urges the spur-wheel 16 forwardly along that shaft and the upper end 21' of the spring 21 10 recoils and thereby withdraws the lug 21" from within the inner space between the frame-plates *a*, *b*, and deprives the On-release arm 48 of the support of the catch-finger 21^x, (compare Figs. 11 and 12), whereby the 15 verge-shaft *s* is permitted to rock and the drive-shaft *d* is made free to rotate and to propel the switch-throwing spindle 36. The electric circuit 55 is now closed at the switch 35 and the bank of energized electric lamps L 20 (Fig. 13) consequently illuminate the show-window of the store, for example. The vibration of the stop-arm 49 having been interrupted by the interposition of the end 44' of the arrester-plate 44 in the path of the toe 25 50 of that stop-arm, the switch-actuating shaft 36 comes to a standstill, while the time-train runs on, turning the spur-gears 16, 24, until the cam-notch 26 cut in the cam-edge 25' of the hub 25 of the spur-wheel 24 is 30 brought opposite the cam-lug 23 carried by the collar 23' fixed on the Off-setting shaft 22 and the upright leaf-spring 28 is thereby made free to shift the rock-shaft *s* to the rear and to release its arms 48, 49. These 35 arms are set vibrating by the engagement of the teeth of the verge-wheel *q* with the noses *r'*, *r''*, of the verge *r*, alternately, as the verge-wheel shaft *o* is propelled by the drive-shaft *d*, the rotation of which is transmitted to the switch-actuating spindle 36, 40 with the result that the switch-blade plate 37 is thrown around another quarter of a full turn and the tongue-like contact-ends 38 of this plate 37 are disconnected from the terminal-plate 39 of the switch 35 (compare Figs. 6 and 7 and see, also, Figs. 3, 5 and 13). The electric circuit 55 is now open at the switch 35. When, as just described, the switch-blade plate 37 is shifted into its circuit-breaking position, one of its ends 38 45 is projected into the path of oscillation of the toe 50 of the stop-arm 49 and checks its back-and-forth movement, whereby the drive-shaft *d* and the switch-turning spindle 36 thereby propelled are arrested, as hereinbefore explained. The time-train continues 50 to propel the Off-control spur-wheel 24, the cam-lug 23 begins to rub against the raised part of the cam-edge or face 25' of the ring-cam or hub 25, the spur-wheel 24 is forced rearwardly and axially along its shaft 22, the bent-lever 30 is rocked on its mid-part 55 30", the rock-shaft *s* moved lengthwise towards the front frame-plate *a*, the switch-shaft stop-arm 49 is carried out of its abut- 60 65 70 75 80 85 90 95 100 105 110 115 120 125 130

ting engagement with the contact-end 38 of the switch-blade plate 37 and into the plane of rotation of the arrester plate 44, and the On-release rocker-arm 48 is shifted over the catch-finger 21^x again and thereby is held against vibratory movement and the verge-wheel shaft *o* and the drive-shaft *d* against rotatory movement, until the catch-finger 21^x is once more jerked from under the On-release arm 48 by the recoil of the flat spring 21 when the cam-notch 19 arrives opposite the cam-lug 20 and the electric circuit 55 is once again closed at the switch 35. The cycle of operations is repeated over and over, so long as the time-train of the clock runs, as will be readily understood by all persons skilled in this art.

The electric-block 54 upon which the clock rests (Fig. 1) is supported by a shelf-bracket 53 fastened to a wall 52; but, of course, any other suitable way of mounting the apparatus C may be adopted, as the exigencies of the particular situation may demand. Between the clock-casing 47 and the electric-block 54, there is interposed a block 58 of electric insulation. (Fig. 5). Instead of the particular form of electric plug or block 54 shown in Fig. 5, any suitable device of this character forming a means of electric connection between the time-switch C and the line may be substituted for the electric block 54; for example, the block illustrated and described in the United States patent granted me April 18, 1916, No. 1,179,512. For the sake of clearness in the drawings, the clock main-spring, the stored energy of which serves to drive the time-train, is not illustrated; but there is shown, in Fig. 2, the head *i''* of the key by means of which the shaft of this main-spring is turned and the main-spring thereby wound up.

The foregoing description, when read in connection with the accompanying drawings, makes clear to all persons skilled in this art how, by the introduction of certain modifications in and additions to the mechanism that controls and times the actuation of the well-known hammer or striker of the alarm-bell in the common so-called "nickel" alarm-clock, that mechanism has, in the hereinbefore-disclosed embodiment of this invention, been altered and adapted and arranged to effect the movement of an electric switch of the rotary type, at predetermined times for the purpose of regulating the automatic making and breaking, at such times, of an electric circuit, that is, without manual control other than that involved in winding-up the motor-springs of the clockwork and the setting of parts of the mechanism so as to bring about the operation of the electric switch at the appointed times.

In accordance with the patent statutes, I have shown and described the preferred form of this invention; yet, however, I de-

sire it to be distinctly understood that I fully realize that changes may be made in the particular embodiment of this invention that is illustrated in the drawings and hereinbefore described, and that I intend to include within the scope of the claims that follow hereinafter, all modifications of the herein disclosed and explained best mode now known to me of applying the principle 10 of this invention that do not depart substantially from the spirit thereof or sacrifice any of the advantages to be derived therefrom.

Having now particularly described the nature of this invention and in what manner the same is to be performed, what I claim as new and desire to secure by Letters Patent is:

1. Time mechanism for controlling the opening and closing of a rotary electric switch, including a time-train; a switch-throwing shaft; driving mechanism by which the switch-throwing shaft is rotated to close and open the switch; verge mechanism operatively connected with the driving mechanism; locking mechanism by which the verge mechanism and the driving mechanism are held arrested when the switch is in open position; releasing mechanism which is controlled by the time-train and by which the locking mechanism is released to permit the driving mechanism to turn the switch-throwing shaft and close the switch; and stop mechanism by which the operation of the driving mechanism is again arrested after the switch is closed thereby.

2. In a time-controlled electric-switch mechanism, the combination of a rotary electric switch with means controlling the operation thereof, said means including a time-train; a switch-throwing shaft; driving mechanism by which the shaft is turned to close and open the switch; locking mechanism by which the operation of the driving mechanism is prevented when the switch is in open position; releasing mechanism which is controlled by the time-train and by means of which the locking mechanism is released to permit the driving mechanism to actuate the switch-throwing shaft and close the switch; means by which such actuation of the switch throwing shaft is arrested when the switch is in closed position; and releasing means by which the last-named means is released to permit the driving mechanism again to turn the switch-throwing shaft in the same direction and thereby to open the switch.

3. In a time-controlled electric-switch mechanism, the combination of an electric switch with means controlling the operation thereof, said means including a time-train; driving mechanism by which the switch is closed and opened; locking mechanism by which the operation of the driving mecha-

nism is prevented when the switch is in open position; releasing mechanism which is controlled by the time-train and by means of which the locking mechanism is released to permit the driving mechanism to close the switch; means by which such actuation of the latter is arrested when the switch is in closed position; releasing means by which the last-named means is released to permit the further actuation of the switch by the driving mechanism until the switch is opened thereby; and stop means by which the said further actuation of the switch is arrested when the switch has been opened.

4. In a time-controlled electric-switch mechanism, the combination of a rotary electric switch with means controlling the operation thereof, said means including a time-train; a switch-throwing shaft; driving mechanism by which the shaft is turned to close and open the switch; locking mechanism by which the operation of the driving mechanism is prevented when the switch is in open position; releasing mechanism which is controlled by the time-train and by means of which the locking mechanism is released to permit the driving mechanism to actuate the switch-throwing shaft to close the switch; means by which such actuation of the switch throwing shaft is arrested when the switch is in closed position; releasing means by which the last-named means is released to permit the driving mechanism again to turn the switch-throwing shaft and thereby to open the switch; and stop means by which the switch-throwing shaft is again arrested when the switch has been opened.

5. In a time-controlled electric-switch mechanism, the combination of an electric switch with means controlling the operation thereof to make and break the circuit, said means including a time-train; driving mechanism by which the switch is actuated; a verge-wheel; a verge-wheel-carrying shaft driven by said mechanism; a rock-shaft; a verge that is mounted on the latter and arranged to cooperate with the verge-wheel; locking mechanism by which the oscillation of the rock-shaft is prevented; releasing mechanism which is controlled by the time-train and by means of which the locking mechanism is released to permit the oscillation of the rock-shaft and the turning of the verge-wheel-carrying shaft and the operation of the driving mechanism and the closing of the switch; and interlocking means by the engagement of which such operation of the switch is arrested, such means being carried by the rock-shaft and the switch.

6. In a time-controlled electric-switch mechanism, the combination of a rotary electric switch with means controlling the operation thereof, said means including a time-train; a switch-throwing shaft; driving

mechanism by which the shaft is turned to actuate the switch; a verge-wheel; a verge-wheel-carrying shaft driven by said mechanism; a rock-shaft; a verge that is mounted on the latter and arranged to cooperate with the verge-wheel; locking mechanism by which the oscillation of the rock-shaft is prevented; releasing mechanism which is controlled by the time-train and by means of which the locking mechanism is released to permit the oscillation of the rock-shaft and the turning of the verge-wheel-carrying shaft and the operation of the driving mechanism and the actuation of the switch-throwing shaft to close the switch; and interlocking means by the engagement of which such operation of the switch-throwing shaft is arrested, such means being carried by the rock-shaft and the switch-throwing shaft.

7. In a time-controlled electric-switch mechanism, the combination of an electric switch with means controlling the operation thereof, said means including a time-train; driving mechanism by which the switch is actuated; a verge-wheel; a verge-wheel-carrying shaft driven by said mechanism; a rock-shaft; a verge that is mounted on the latter and arranged to cooperate with the verge-wheel; locking mechanism by which the oscillation of the rock-shaft is prevented; releasing mechanism which is controlled by the time-train and by means of which the locking mechanism is released to permit the oscillation of the rock-shaft and the turning of the verge-wheel-carrying shaft and the operation of the driving mechanism and the actuation of the switch; interlocking means by the engagement of which the operation of the switch is arrested, such means being carried by the rock-shaft and the switch; and releasing means by means of which the interlocking means are disengaged from each other to permit the further actuation of the switch by the driving mechanism.

8. In a time-controlled electric-switch mechanism, the combination of a rotary electric switch with means controlling the operation thereof, said means including a time-train; a switch-throwing shaft; a driving mechanism by which the shaft is turned to actuate the switch; a verge-wheel; a verge-wheel-carrying shaft driven by said mechanism; a rock-shaft; a verge that is mounted on the latter and arranged to cooperate with the verge-wheel; locking mechanism by which the oscillation of the rock-shaft is prevented; releasing mechanism which is controlled by the time-train and by means of which the locking mechanism is released to permit the oscillation of the rock-shaft and the turning of the verge-wheel-carrying shaft and the operation of the driving mechanism and the actuation of the switch-throwing shaft to operate the switch; interlocking means by the engagement of which the operation of the switch-throwing shaft is arrested, such means being carried by the rock-shaft and the switch-throwing shaft; and releasing means by which the interlocking means are disengaged from each other to permit the further actuation of the switch-throwing shaft by the driving mechanism and the further operation of the switch thereby through the last-named shaft.

9. In a time-controlled electric-switch mechanism, the combination with an electric switch and driving mechanism therefor, of a rock-shaft arranged to be oscillated by the driving mechanism; locking mechanism by which the rock-shaft is locked against oscillatory movement and the driving mechanism is maintained inoperative; a time-train; time-train-controlled releasing mechanism by which the rock-shaft is released and permitted to oscillate and the driving mechanism is made free to operate the switch; a stop-device carried by the rock-shaft; and an arrester-device carried by the switch and arranged to be thrown into interlocking engagement with the stop-device by the circuit-closing movement of the switch and to arrest the further operation of the switch by the driving mechanism.

10. In a time-controlled electric-switch mechanism, the combination with an electric switch and driving mechanism therefor, of a lengthwise-shiftable rock-shaft; interlocking stop-devices which are carried by the rock-shaft and the switch and which are susceptible of being disengaged from each other by the lengthwise shifting of the rock-shaft and by the engagement of which the rock-shaft is prevented from oscillating and the driving mechanism from actuating the switch; a time-train; and time-train-controlled mechanism by which the rock-shaft is shifted lengthwise and the interlocking devices are disengaged from each other to permit the oscillation of the rock-shaft and the actuation of the switch by the driving mechanism.

11. In a time-controlled electric-switch mechanism, the combination with an electric switch and driving mechanism therefor, the switch being provided with a circuit-closing device; of a rock-shaft arranged to be oscillated by the driving mechanism; a stop-device carried by the rock-shaft; a time-train; and time-train-controlled mechanism by which the stop-device is interposed in the path of the circuit-closing device and said devices are brought into interlocking engagement and the switch is brought to rest.

12. In a time-controlled electric-switch mechanism, the combination with an electric switch and driving mechanism therefor; of a rock-shaft arranged to be oscillated by the driving mechanism and to be shifted length-

wise; a stop device carried by the rock-shaft; a time-train; and time-train-controlled mechanism by which the stop-device is interlocked with the switch by shifting 5 the rock-shaft lengthwise and the driving mechanism is made inoperative and the switch is arrested.

13. In a time-controlled electric-switch mechanism, the combination with an electric 10 switch and driving mechanism therefor; of a lengthwise-shiftable rock-shaft arranged to be oscillated by the driving mechanism when the latter actuates the switch; interlocking devices by the engagement of which the 15 rock-shaft is locked against oscillatory movement and the driving mechanism is made inoperative; a stop-device carried by the rock-shaft and arranged to enter into interlocking engagement with the switch and thereby 20 to prevent the actuation of the same by the driving mechanism when the interlocking devices are disengaged from each other; a time-train; and time-train-controlled mechanism by which the rock-shaft is shifted 25 lengthwise and the stop-device is freed from interlocking engagement with the switch and the interlocking devices are brought into interlocking engagement to prevent the oscillation of the rock-shaft and the actuation 30 of the switch.
14. In a time-controlled electric-switch mechanism, the combination of an electric switch with means controlling the operation thereof to open and close the switch, said 35 means including a time-train; driving mechanism by which the switch is actuated; a plurality of locking mechanisms by which the actuation of the switch is prevented; on-mechanism which is controlled by the 40 time-train and by which one of the locking mechanisms is momentarily released to permit the driving mechanism to close the switch; and off-mechanism which is controlled also by the time-train and by which 45 the other of the locking mechanisms is released momentarily to permit the driving mechanism to open the switch again.

15. In a time-controlled electric-switch mechanism, the combination of an electric switch with means controlling the operation 50 thereof to open and close the switch, said means including a time-train; driving mechanism by which the switch is actuated; locking devices by which the actuation of the switch is prevented; on-mechanism by which 55 the locking devices are momentarily released to permit the driving mechanism to close the switch; off-mechanism by which the locking devices are momentarily released again to permit the driving mechanism 60 again to open the switch; and means by which the on and off mechanisms are operatively connected to permit one of them to drive the other therethrough and the time-train to control both of them. 65

16. In a time-controlled electric-switch mechanism, the combination of an electric switch with means controlling the operation thereof to open and close the switch, said 70 means including a time-train; driving mechanism by which the switch is actuated; a verge-wheel; a verge-wheel-carrying shaft driven by said mechanism; a rock-shaft; a verge mounted on the latter and arranged to cooperate with the verge-wheel; locking 75 devices by which the actuation of the switch is prevented; on-mechanism by which the locking devices are momentarily released to permit the driving mechanism to close the switch and which is controlled by the time-train; and off-mechanism which is controlled 80 by the time-train and by which the locking devices are again momentarily released to permit the driving mechanism to open the switch again; one of said mechanisms by 85 which the locking devices are released including means by which the rock-shaft is shifted to permit the driving mechanism to operate the switch.

Signed at Jackson, in the county of Jackson, 90 and State of Ohio, this 11th day of July, A. D. 1923.

LOUIS T. FENNING.
